(57) **CLAIM**

The ornamental design for a detachable face for a lighting softbox, as shown and described.

DESCRIPTION

FIG. 1 is a front perspective view of a detachable face for a lighting softbox;

FIG. 2 is a front elevation view of the detachable face for a lighting softbox of FIG. 1;

FIG. 3 is rear elevation view of the detachable face for a lighting softbox of FIG. 1;

FIG. 4 is a left elevation view of the detachable face for a lighting softbox of FIG. 1;

FIG. 5 is a right elevation view of the detachable face for a lighting softbox of FIG. 1;

FIG. 6 is a top plan view of the detachable face for a lighting softbox of FIG. 1;

FIG. 7 is a bottom plan view of the detachable face for a lighting softbox of FIG. 1; and,

FIG. 8 is a front perspective view of the detachable face for a lighting softbox of FIG. 1 positioned on a lighting softbox. The broken lines shown in the FIG. 1 and FIG. 8 depict portions of the detachable face for a lighting softbox and forms no part of the claimed design. The additional broken lines seen in FIG. 8 are for the purposes of disclosing environment and forms no part of the claimed design.

1 Claim, 6 Drawing Sheets
